UNITED STATES PATENT OFFICE.

THOMAS BEARY HOLMES, OF CHARLESTON, MISSISSIPPI.

SAW-HANDLE.

1,260,198.

Specification of Letters Patent. Patented Mar. 19, 1918.

Application filed February 1, 1917. Serial No. 145,929.

To all whom it may concern:

Be it known that I, THOMAS B. HOLMES, a citizen of the United States, residing at Charleston, in the county of Tallahatchie 5 and State of Mississippi, have invented certain new and useful Improvements in Saw-Handles; and I do declare the following to be a full, clear, and exact description of the invention, such as will enable others skilled 10 in the art to which it appertains to make and use the same.

This invention relates to new and useful improvements in saw handles and more particularly to a saw handle adapted to be applied to a cross cut saw, and which is capable 15 of being adjustable for either cutting logs on the ground or for cutting down trees.

A further object of the invention is to provide a saw handle of this character which 20 is adapted to be readily attached or detached from a saw.

Another object of the invention is to provide a device of this character which is simple and durable in construction, inexpensive 25 to manufacture, and one which will be very efficient in operation.

With these and numerous other objects in view, my invention consists of the novel 30 features of construction, combination and arrangement of parts which will be herein referred to and more particularly pointed out in the specification and claim.

In the accompanying drawings:—

Figure 1 is a side elevation of the handle; 35 Fig. 2 is a vertical section; Fig. 3 is a horizontal section on the line 3—3 of Fig. 1;

Fig. 4 is a front elevation of the front washer;

Fig. 5 is a side view of the handle.

Corresponding and like parts are referred to in the following description and indicated in all the views of the drawings by the same reference characters.

The device comprises a handle 1 which is formed of wood, or any other desired material, and which is provided adjacent its lower end with a longitudinally extending flat-sided slot 2 therein. Positioned on the 45 lower end of the handle 1 is a sleeve 3 which is provided with alining longitudinally extending openings 4 therein which are adapted to be positioned adjacent the opposite ends of the slot through the handle, and 50 which alines with the same. This sleeve 3 is

secured on the handle by rivets 5 or any other desired type of fastening means.

A saw bolt 6 is adapted to be positioned through the slot in the handle, and this bolt is provided with a substantially rectangular-shaped portion 7 which is adapted to have two of its opposite sides engage the slot in the handle, and the end of this portion 7 that projects from the handle is provided with an enlarged head portion 8. This portion 65 7 of the bolt 6 has a longitudinally extending slot 9 therein extending from one end, and the slotted portion of the head 8 is adapted to receive one end of a cross cut saw 10 therein. The head 8 is provided with 70 alining openings 11 therethrough, and these openings are adapted to aline with an opening in the end of the saw, and a fastening pin 12 is positioned through the same to securely hold the end of the saw in engagement with the head. The remaining portion of the bolt 6 is externally threaded as shown at 13, and is adapted to project from the opposite side of the slot in the handle from which the rectangular-shaped portion 80 extends.

The bolt 6 is provided with a pair of curved washers 14 and 15, the washer 14 being positioned on the side of the handle adjacent the end of the saw, and being called 85 the front washer, while the washer 15 engages the rear side of the handle. These washers 14 and 15 are provided with laterally projecting bosses 16 that have alining 90 openings therein, the opening in the washer 14 being substantially rectangular-shaped to receive the correspondingly shaped portion of the bolt, while the opening in the washer 15 is correspondingly shaped to the portion 13 of the bolt 6 to receive the same. The 95 head 8 as illustrated in Fig. 3 is adapted to engage the base of the adjacent washer 14 and the various parts are clamped in locked relation with each other by means of a clamping wing nut 17 that operatively engages the threaded portion 13 of the saw bolt.

The front washer 14 is provided in its outer surface with a longitudinally extending vertical slot 18 which intersects the centrally disposed opening therethrough, and which is adapted to receive the rear edge of the saw 10, when said saw is locked in the head of the bolt. This washer also is provided with an integral laterally projecting 110

trough-shaped guard 19 that extends at an angle from the adjacent lower end of the washer straddling the lower end of the slot 18 and which is adapted to receive the teeth of the saw therein that are adjacent the connected end. This guard will form a covering for the teeth and prevent the operator from being accidentally injured by the same.

In operation, when it is desired to place 10 the handle in position on the saw, the front washer 14 is placed over the slot, and the bolt is then positioned through the opening in the washer and the slot. The rear washer 15 is then placed on the bolt, and the wing nut 16 is tightened up to clamp the parts in position. It will be understood that when the bolt is first placed in position, the same is brought into engagement with the end of the cross saw, and locked thereto by means of 20 the locking pin 12 extending through the headed portion that engages the saw.

Upon loosening the nut 17 from engagement with the rear washer, the bolt is adapted to be adjustable longitudinally within 25 the slot, so that the saw may be adjusted for cutting either logs on the ground or cutting down trees. The saw is held by this device tightly against the handle, and owing to the fact that one portion of the bolt running 30 through the slot is rectangular-shaped and engages the flat sides of said slot and a correspondingly shaped hole in the washer, the bolt will be prevented from turning on the handle and working loose.

If desired, the trough-shaped guard on 35 the front washer may be eliminated, but it is preferably made an integral part of the same, as it affords ample protection for the saw teeth that are disposed directly adjacent the handle, and prevents the operator

from accidentally engaging these teeth and any injury suffered therefrom. This guard also will protect the teeth it covers while serving to guide the end of the saw into the slot 18.

From the foregoing description of the construction and operation of my new and improved saw handle, the manner of applying the same to use and the operation thereof will be readily understood, and it will be 50 seen that I have provided a simple and efficient means for carrying out the objects of the invention.

I claim:—

The combination with a saw handle having 55 therein a longitudinal rectangular slot, a rectangular bolt slideable longitudinally and laterally in the slot and projecting from both sides of the handle, said bolt being split longitudinally from one end to receive 60 a saw blade and enlarged clamping heads on the ends of said split portions, a curved washer having a slot to receive the split portions and a boss to engage the enlarged 65 heads disposed between the handle and said 70 enlarged portions of the bolt, said washer having a troughed integral guard extending laterally from its lower end to receive and guide a saw blade, the other end of said bolt being threaded, a curved washer disposed on 75 said bolt having a slot therein to receive the bolt, and a nut on said bolt to lock said blade to the handle.

In testimony whereof I have hereunto set 75 my hand in the presence of two subscribing witnesses.

TOM BEARY HOLMES.
